Primary Examiner — Susan Moon Lee(74) *Attorney, Agent, or Firm* — Paul M. Thompson; Cochran Freund & Young LLC(57) **CLAIM**

The ornamental design for an animal watering device, as shown and described.

DESCRIPTION

FIG. 1 is an isometric view of an animal watering device showing my new design.

FIG. 2 is a front elevation view thereof.

FIG. 3 is a top plan view thereof.

FIG. 4 is a left side elevation view thereof.

FIG. 5 is a right side elevation view thereof.

FIG. 6 is a rear elevation view thereof; and,

FIG. 7 is a bottom plan view thereof.
